UNITED STATES PATENT OFFICE.

ALLEN J. PATCH, OF RIPON, WISCONSIN.

INTERNAL-COMBUSTION ENGINE.

Application filed August 10, 1926. Serial No. 128,447.

The present invention relates to improvements in internal combustion engines of the four-cycle type in which the intake and exhaust of the motive gases are controlled by a single tubular sleeve interposed between the piston and the walls of the cylinder which is reciprocated to open and close the intake and exhaust ports.

The superiority of a reciprocating sleeve valve to control the intake and exhaust of the motive gases over the more common form of poppet valve has been distinctively proven, but it has been found impossible with the linkage arrangement heretofore employed to properly operate a single sleeve valve so as to hold the sleeve without movement during the period of high pressure in the cylinder, and thereby obtain the maximum power on the expansion stroke. This is clearly recognized and set forth in the patent to Urtel, No. 1,156,508, in which it is proposed to overcome this difficulty by making the intake and exhaust ports further apart so that the movement of the sleeve during the period of high pressure in the cylinder will not uncover either of the ports during that period. While such an arrangement prevents the ports from becoming uncovered, and retains the motive gases within the combustion chamber during the period of high pressure, the spacing of the intake and exhaust ports a greater distance apart adversely effects the timing of the valve, since the greater the distance between the ports, the further the valve will have to travel after closing the exhaust port before it opens the intake port, thereby resulting in either an early closing of the exhaust or a late opening of the intake. It is an object of my invention to provide a linkage arrangement for reciprocating the sleeve valve, by which the valve is given an irregular reciprocatory movement, and is held stationary at a point between the inlet and exhaust positions, the maximum power thereby being obtained during the expansion stroke, with the development of no interference with the timely opening and closing of the intake and exhaust ports. It is further contemplated that the opening and closing of the ports will be with such rapidity that the greatest possible area of opening will be obtained, up to the respective points of closing and opening.

Another object of my invention is the

provision of a single reciprocating sleeve valve having a single row of openings distributed uniformly around the sleeve, through which openings the intake and exhaust gases alternately pass. By arranging the openings in this manner it is possible to seal them with a junk ring during the power stroke, and to arrange the intake and exhaust openings uniformly on opposite sides of the cylinder, permitting their area to be thereby doubled. A further advantage in having the openings thus arranged is that the portion of the sleeve which is exposed to the heat of the exhaust gases will also be alternately subjected to the cooling effect of the incoming fuel mixture, which, to a considerable extent, will counteract the effect of the hot exhaust gases, and any distortion which might arise from exposing the parts on one side to the heat of the exhaust only, and those on the other side to the cooling effect of the intake only, will be prevented.

As commonly constructed, engines utilizing such reciprocating slide valves have been designed so that the intake is closed by the upward movement of the sleeve within the cylinder. Such a construction makes it necessary, as the piston approaches the end of the intake stroke, for the incoming charge to pass over the top of the lower wall defining the opening in the sleeve while it is approaching the upper side of the port in the cylinder. At this same time the velocity of the mixture is being reduced and the heavier particles of the fuel impinge against the wall of the sleeve instead of going over the top and into the combustion chamber, thereby giving a diluted mixture in the combustion chamber and also interfering with the proper lubrication of the sleeve valve.

A further object of my invention is to provide an internal combustion engine having a reciprocating sleeve valve which closes the intake port by a downward movement of the sleeve, whereby the lower side of the intake passage is swept clean until the moment at which the port completely closes. The heavier particles of the fuel are thereby carried into the combustion chamber instead of settling to the floor of the intake port, and a sufficiently rich charge is at all times assured and any adverse interference with the lubrication of the sleeve prevented.

While some of the objects of my invention have already been pointed out, other objects and advantages will be readily appreciated by a reference to the accompanying specification and the drawings forming a part thereof, in which,

Figure 1 is a vertical cross sectional view through an engine cylinder embodying my invention, the parts being shown in the position assumed during the power stroke.

Fig. 2 is a view similar to Fig. 1, with the parts shown in the position assumed during the intake stroke.

Figs. 3, 4, 5 and 6 are diagrammatic views of the position of the links for operating the sleeve valve during the intake, compression, expansion and exhaust strokes, respectively, of the engine; and

Fig. 7 is the projected valve motion curve produced by my linkage arrangement.

By referring to Figs. 1 and 2 it will be noted that the engine comprises the usual cylinder 1, piston 2, connecting rod 3 and crankshaft 4. Interposed between the piston 2 and the walls of the cylinder 1 is a reciprocating tubular sleeve valve 5, provided near its upper end with a plurality of openings 16 uniformly distributed around its periphery in a horizontal plane. These openings are adapted to alternately register with a plurality of intake and exhaust ports 7 and 8 which are likewise uniformly distributed around the cylinder 1. The intake ports 7 are arranged above the exhaust ports 8, but are separated therefrom only a sufficient distance to provide for the lap of the ports. This is possible, due to the novel linkage arrangement for reciprocating the sleeve valve 5, to be presently described, which holds the valve without movement during the period of high pressure in the cylinder between the intake and exhaust strokes.

It is particularly desirable that the openings 6 in the sleeve valve 5 be in the same horizontal plane, as this makes it possible to seal them during the power stroke by means of a junk ring 9, located within the combustion chamber and preferably supported from the cylinder head 10 by depending arms 11, and which comprises an annular ring 12 having a recess 13 into which is fitted the packing ring 14. By reference to Fig. 1 it will be seen that when the parts are in the position assumed during the power stroke, the openings 6 in the sleeve 5 are effectively sealed between the junk ring and that portion of the cylinder wall between the intake and exhaust ports 7 and 8, and as the valve is given no movement at this time, the openings will remain sealed during substantially the entire period of high pressure within the cylinder. The arrangement of the openings 6 in a horizontal plane also permits the intake and exhaust ports to be

formed in opposite sides of the cylinder, thereby permitting the area of those openings to be doubled.

By utilizing the same openings in the sleeve valve for admitting the combustible mixture into and for exhausting the spent gases from the combustion chamber, the heating effect of the exhaust gases is to a large degree counteracted by the cooling effect of the incoming gases, and as these openings are distributed uniformly around the sleeve, any distortion which would result from exposing the ports on one side to the heat of the exhaust only, and those on the other side to the cooling effect of the incoming gases only is eliminated.

The means for imparting the desired reciprocating movement to the sleeve valve 5 comprises a sprocket gear 15 located on the crankshaft 4, about which passes the sprocket chain 16. The other end of the sprocket chain 16 passes around a relatively large sprocket gear 17, fast on one end of the stub shaft 18, which shaft is driven at one half the speed of the crankshaft 4. Rigidly secured to the other end of the shaft 17 is a crank 19 having connected thereto a connecting rod 20, the outer end of which is pivotally connected to one end of the link 21. The other end of the link 21 is pivotally connected to the sleeve 5 at the point *c* and causes the reciprocation of the sleeve. While the means for imparting movement to the connecting rod and ultimately the sleeve 5 is shown and herein described as a simple crank, it is obvious that a wheel crank or an eccentric may be substituted therefor.

As the order of the four strokes are exhaust, intake, compression and expansion, it is necessary that the valve be in one extreme position during the exhaust stroke and in the other extreme position during the next or intake stroke. It is, therefore, obvious that if the movement imparted to the sleeve 5 were a uniform, uninterrupted reciprocating motion, the intake and exhaust ports would again be opened during the next two, or the compression and expansion strokes. It is, therefore, necessary that the movement of the sleeve valve 5 be interrupted between the next two strokes at a point between the intake and exhaust positions. In order to accomplish this interrupted reciprocatory movement of the sleeve valve, I provide the link 22, which is pivoted at one end to a fixed pivot 23, and which has its other end pivotally connected to the connecting rod 20 at *b*. The rotation of the crank 19 causes a resultant movement of the connecting rod 20, and the link 22 having one end pivoted thereto and the other end pivoted to the fixed pivot 23, swings about said pivot and controls the movement of the connecting rod 20 and link 21 and consequently the movement of the sleeve 5, thereby causing the sleeve to

- be given an interrupted reciprocatory motion and also causing it to remain stationary during the period of high pressure in the cylinder between the intake and exhaust strokes. By thus holding the sleeve 5 substantially stationary during the period of high pressure in the cylinder, it is possible to reduce the distance between the intake and exhaust ports to the bare minimum necessary to provide the lap on the ports. By providing this interrupted reciprocatory movement of the sleeve 5 and by bringing the intake and exhaust ports close together, a rapid opening and closing of the ports with the greatest possible area of opening, up to the respective points of closing and opening, is obtained, and the ports are positively opened and closed at the correct time in relation to the crank cycle.
- By referring to Figs. 3, 4, 5 and 6, it will be readily seen how the arrangement of the operating links causes the irregular reciprocatory movement of the sleeve. In Fig. 3 the parts are shown in the position assumed during the intake stroke and with the opening 6 registering with the intake ports 7. In this position, the sleeve 5 is in the extreme upper position, the link 22 is substantially vertical, and the point *a* on the crank at its lowermost position. As the crank rotates, the point *a* at the inner end of the connecting rod 20 moves to the left and upwardly, and the link 22 moves to the left of the vertical. At the same time the link 21 has been moved to the left and drawn downwardly, which movement in turn causes the sleeve 5 to reciprocate until it was brought into the position shown in Fig. 4; at that time the compression in the cylinder takes place. From the position shown in Fig. 4, the point *a* begins an upward movement and the connecting rod 22 moves to the right until it again assumes the substantially vertical position shown in Fig. 5. The combined movement of the points *a* and *b* results in the point *c*, where the connecting rod 21 is pivoted to the connecting rod 20, being moved in an arc *d* with the point *c* as its center, and with the arm 21 imparting no movement whatever to the sleeve 5 during this period, as is clearly seen by comparing Fig. 4 with Fig. 5, which shows the relative position of the parts during the expansion stroke. Further rotation of the crank now causes movement of both the point *a* and the point *b*, with a resulting quick downward movement of the link 21 and of the sleeve 5 until the sleeve is brought into the position shown in Fig. 6, with the openings 6 therein registering with the exhaust ports 8, at which time the exhaust of the spent gases begins. At that time, the point *a* on the crank is slightly above the horizontal. As the exhaust of the spent motive gases takes place, the crank 19 continues its movement until the point *a* descends below the horizontal and begins a downward movement which results in the inner end of connecting rod 20 being pulled back and downwardly and the point *b* being moved backward and upwardly. This combined movement of points *a* and *b* results in the connecting rod 21 being rapidly raised upward and the sleeve being quickly moved from its extreme power position, which it assumes on the exhaust stroke, to the extreme upper portion ready for the intake of the next cycle.
- It will be noted by referring to Figs. 3 and 4 that the intake port 7 is closed by a downward movement of the sleeve 5. By thus having the intake 7 closed by a downward movement of the sleeve, the heavier particles of fuel, which at the end of the intake tend to settle to the bottom of the port due to the decrease of velocity of the mixture, will be completely swept from the floor of the intake port 7 until the upper edges of the openings 6 descend entirely below the lower side thereof, thereby assuring a sufficiently rich mixture within the combustion chamber at all times and preventing any liquid hydrocarbon finding its way between the sleeve 5 and the cylinder walls 1 to adversely affect the lubrication of the sleeve.
- The diagram of Fig. 7 represents the different phases of the movement of the valve when actuated with a linkage arrangement as above described. In this diagram, the upper and lower dead centers of the crank 100 shaft 4 are indicated by the lines 24 and 25 respectively, and the movement of the valve by the curved line. It will be noted that after the intake once begins to open, the movement of the valve is rapid until it has nearly reached the point of maximum opening. The movement is then slightly arrested in order to allow a sufficient amount of fuel mixture to be drawn into the combustion chamber, after which the valve is rapidly closed. The opening and closing of the inlet is represented on the curve by the numerals 27 and 28. From the point 28 where the intake closes, the movement of the valve is very slow until it reaches the point 29, at which it comes to rest and remains stationary until the point 30 is reached. The distance on the curve between the points 29 and 30 represents the period of maximum pressure in the cylinder between the intake and exhaust strokes. From the point 30 the valve maintains a slow movement until the exhaust opens, which is represented by the point 31. From this point the movement of the valve is again accelerated to give a rapid opening and closing of the exhaust and to return the valve to the other extreme end of the cylinder to open the intake for the next cycle.
- It will thus be seen that the linkage ar-

130

arrangement of this invention produces a valve motion curve which substantially conforms to that which has been considered the theoretical curve to which approximation should be made, but which has been unobtainable with any linkage arrangement heretofore devised.

While I have described my invention in connection with the preferred arrangement 10 of parts, it is to be understood that this disclosure is illustrative only and that the invention can be carried out by other arrangements within the scope of the appended 15 claims, which will impart the desired interrupted reciprocating movement to the sleeve valve, and which will provide for the proper sealing of the ports and the opening of the intake by a downward movement of the sleeve.

20 The term "irregular reciprocating movement" as hereinafter used in some of the claims to describe the movement of the sleeve valve, is used to designate a reciprocatory motion which is arrested at certain periods 25 to cause the sleeve valve to remain stationary, or a reciprocatory motion which merely slows down the movement of the sleeve at certain periods, while the term "interrupted reciprocatory motion" is used to define specifically a reciprocatory motion which is interrupted and brought to a stop at a certain 30 period of the cycle.

What I claim is:

1. In an internal combustion engine having admission and exhaust ports through its 35 wall, a slide valve controlling said ports, and a simple crank and linkage for giving said valve an interrupted reciprocatory motion.

2. In an internal combustion engine having admission and exhaust ports through its 40 wall, a slide valve controlling said ports, and means for giving said valve an irregular reciprocatory motion comprising a shaft driven by the engine, a crank operated by 45 said shaft, a link connecting said crank to the slide valve and a second link controlling the movement of the first mentioned link.

3. In an internal combustion engine having admission and exhaust ports through its 50 wall, a slide valve controlling said ports, and means for giving said valve an irregular reciprocatory motion comprising a shaft driven by the engine, a crank operated by 55 said shaft, a link connecting the crank to the slide valve and a second link controlling the movement of the first mentioned link, said second link having one end thereof secured to a fixed pivot.

4. In an internal combustion engine having admission and exhaust ports through its 60 wall, a slide valve controlling said ports, and means for giving said valve an irregular reciprocatory motion comprising a shaft driven by the engine, a crank operated by 65 said shaft, a link pivoted at one end to the

crank and at its other end to the slide valve, and a second link pivoted at one end to a fixed pivot and at its other end to the crank for controlling the movement of the first mentioned link.

70

5. In an internal combustion engine having admission and exhaust ports through its wall, a slide valve controlling said ports, and means for giving said valve an irregular reciprocatory motion comprising a shaft 75 driven at engine speed, a half-speed shaft, a crank on the half-speed shaft, a link connecting the crank to the slide valve and a second link controlling the movement of the first mentioned link.

80

6. In an internal combustion engine having admission and exhaust ports through its wall, a slide valve controlling said ports, and means for giving said valve an irregular reciprocatory motion comprising a shaft 85 driven at engine speed, a half-speed shaft, a crank on the half-speed shaft, a link connecting the crank to the slide valve and a second link controlling the movement of the first mentioned link, said second link having 90 one end thereof secured to a fixed pivot.

90

7. In an internal combustion engine having admission and exhaust ports through its wall, a slide valve controlling said ports, and means for giving said valve an irregular 95 reciprocatory motion comprising a shaft driven at engine speed, a half-speed shaft, a crank on the half-speed shaft, a link connecting the crank to the slide valve, and a second link pivoted at one end to a fixed 100 pivot and at its other end to the crank.

100

8. In an internal combustion engine having admission and exhaust ports through its wall, a piston, a tubular slide valve arranged between the piston and the cylinder 105 wall and controlling said ports, and means for giving said valve an irregular reciprocatory motion comprising a shaft driven at engine speed, a half-speed shaft driven from said first mentioned shaft, a crank on the 110 half-speed shaft, a connecting rod thereon, a link connecting said connecting rod and the slide valve, and a second link pivoted at one end to a fixed pivot and at its other end to the connecting rod.

115

9. In an internal combustion engine having admission and exhaust ports through its wall, a piston, a tubular slide valve arranged between the piston and the cylinder 120 wall and controlling said ports, and means for giving said valve an irregular reciprocatory motion comprising a shaft driven at engine speed, a half-speed shaft driven from said first mentioned shaft, a crank on the half-speed shaft, a connecting rod thereon, a link connecting the outer end of said arm and the slide valve and a second link pivoted at one end intermediate the ends 125 of the connecting rod and at its other end to a fixed pivot.

130

10. In internal combustion engine having admission and exhaust ports through its wall, a slide valve having openings adapted to register alternately with the admission and exhaust ports, and a single crank and linkage for giving said valve an interrupted reciprocatory motion. 70
11. In an internal combustion engine having a plurality of admission and exhaust ports through its wall, a slide valve having a plurality of openings adapted to register alternately with the admission and exhaust ports, and a single crank and linkage for giving said valve an interrupted reciprocatory motion. 75
12. In an internal combustion engine having a plurality of admission and exhaust ports arranged respectively in different horizontal planes about the cylinder wall, a slide valve having a plurality of openings adapted to register alternately with the admission and exhaust ports, and a single crank and linkage for giving said valve an interrupted reciprocatory motion. 80
13. In an internal combustion engine having admission and exhaust ports through its wall adjacent the head of the cylinder, a piston, a tubular slide valve arranged between the piston and the cylinder wall having a plurality of openings adapted to register alternately with the admission and exhaust ports, and a single crank and linkage for giving said valve an interrupted reciprocatory motion. 90
14. In an internal combustion engine having a plurality of admission and exhaust ports through its wall, adjacent the head of the cylinder, a piston, a tubular slide valve arranged between the piston and the cylinder wall having a plurality of openings adapted to register alternately with the admission and exhaust ports and means for giving said slide valve an irregular reciprocatory motion comprising a shaft driven by the engine, a crank operated by said shaft, a link connecting the crank to the slide valve and a second link controlling the movement of the first mentioned link. 100
15. In an internal combustion engine having a plurality of admission and exhaust ports through its wall, adjacent the head of the cylinder, a piston, a tubular slide valve arranged between the piston and the cylinder wall having a plurality of openings adapted to register alternately with the admission and exhaust ports and means for giving said slide valve an irregular reciprocatory motion comprising a shaft driven by the engine, a crank operated by said shaft, a link connecting the crank to the slide valve and a second link controlling the movement of the first mentioned link, said second link having one end thereof secured to a fixed pivot. 110
16. In an internal combustion engine having a plurality of admission and exhaust ports through its wall, adjacent the head of the cylinder, a piston, a tubular slide valve arranged between the piston and the cylinder wall having a plurality of openings adapted to register alternately with the admission and exhaust ports and means for giving said slide valve an irregular reciprocatory motion comprising a shaft driven at engine speed, a half-speed shaft, a crank on the half-speed shaft, a link connecting the crank to the slide valve, and a second link controlling the movement of the first mentioned link. 115
17. In an internal combustion engine having a plurality of admission and exhaust ports through its wall, adjacent the head of the cylinder, a piston, a tubular slide valve arranged between the piston and the cylinder wall having a plurality of openings adapted to register alternately with the admission and exhaust ports and means for giving said slide valve an irregular reciprocatory motion comprising a shaft driven at engine speed, a half-speed shaft, a crank on the half-speed shaft, a link connecting the crank to the slide valve and a second link controlling the movement of the first mentioned link. 95
18. In an internal combustion engine having a plurality of admission and exhaust ports through its wall, adjacent the head of the cylinder, a piston, a tubular slide valve arranged between the piston and the cylinder wall having a plurality of openings adapted to register alternately with the admission and exhaust ports and means for giving said slide valve an irregular reciprocatory motion comprising a shaft driven at engine speed, a half-speed shaft, a crank on the half-speed shaft, a link connecting the crank to the slide valve, and a second link controlling the movement of the first mentioned link, said second link having one end thereof secured to a fixed pivot. 105
19. In an internal combustion engine having a plurality of admission and exhaust ports through its wall, adjacent the head of the cylinder, a piston, a tubular slide valve arranged between the piston and the cylinder wall having a plurality of openings adapted to register alternately with the admission and exhaust ports and means for giving said slide valve an irregular reciprocatory motion comprising a shaft driven at engine speed, a half-speed shaft driven from said first mentioned shaft, a crank on the half-speed shaft having a connecting rod connected thereto, a link connecting said connecting rod and the slide valve and a second link pivoted at one end to a fixed pivot and at its other end to the connecting rod. 120
20. In an internal combustion engine having a plurality of admission and exhaust ports through its wall, adjacent the head of the cylinder, a piston, a tubular slide valve arranged between the piston and the cylinder wall having a plurality of openings adapted to register alternately with the admission and exhaust ports and means for giving said slide valve an irregular reciprocatory motion comprising a shaft driven at engine speed, a half-speed shaft driven from said first mentioned shaft, a crank on the half-speed shaft having a connecting rod connected thereto, a link connecting said connecting rod and the slide valve and a second link pivoted at one end to a fixed pivot and at its other end to the connecting rod. 125
21. In an internal combustion engine having a plurality of admission and exhaust ports through its wall, adjacent the head of the cylinder, a piston, a tubular slide valve arranged between the piston and the cylinder wall having a plurality of openings adapted to register alternately with the admission and exhaust ports and means for giving said slide valve an irregular reciprocatory motion comprising a shaft driven at engine speed, a half-speed shaft driven from said first mentioned shaft, a crank on the half-speed shaft having a connecting rod connected thereto, a link connecting said connecting rod and the slide valve and a second link pivoted at one end to a fixed pivot and at its other end to the connecting rod. 130

20. In an internal combustion engine having a plurality of admission and exhaust ports through its wall, adjacent the head of the cylinder, a piston, a tubular slide valve arranged between the piston and the cylinder wall having a plurality of openings adapted to register alternately with the admission and exhaust ports and means for giving said slide valve an irregular reciprocatory motion comprising a shaft driven at engine speed, a half-speed shaft driven from said first mentioned shaft, a crank on the half-speed shaft having a connecting rod connected thereto, a link connecting the outer end of said connecting rod and the slide valve and a second link pivoted at one end intermediate the ends of the connecting rod and at its other end to a fixed pivot.
- 10 21. In an internal combustion engine of the four-cycle type having admission and exhaust ports extending through the wall of
- the cylinder, a slide valve controlling said ports, means for imparting a reciprocatory motion to the slide valve, and a single crank 25 and linkage for causing the movement of the slide valve to be arrested for a period between the intake and the exhaust.
- 15 22. In an internal combustion engine of the four-cycle type having admission and exhaust ports extending through the wall of the cylinder, a slide valve controlling said ports, means for imparting a reciprocatory motion to the slide valve, and means for causing the movement of the slide valve 30 to be arrested for a period between the intake and the exhaust, comprising a link pivoted at one end to a fixed pivot and having its other end connected to the means for imparting the reciprocatory motion to the 35 slide valve.
- 20

In testimony whereof I affix my signature.

ALLEN J. PATCH.

20. In an internal combustion engine having a plurality of admission and exhaust ports through its wall, adjacent the head of the cylinder, a piston, a tubular slide valve arranged between the piston and the cylinder wall having a plurality of openings adapted to register alternately with the admission and exhaust ports and means for giving said slide valve an irregular reciprocatory motion comprising a shaft driven at engine speed, a half-speed shaft driven from said first mentioned shaft, a crank on the half-speed shaft having a connecting rod connected thereto, a link connecting the outer end of said connecting rod and the slide valve and a second link pivoted at one end intermediate the ends of the connecting rod and at its other end to a fixed pivot.
- 10 21. In an internal combustion engine of the four-cycle type having admission and exhaust ports extending through the wall of
- 15 the cylinder, a slide valve controlling said ports, means for imparting a reciprocatory motion to the slide valve, and a single crank 25 and linkage for causing the movement of the slide valve to be arrested for a period between the intake and the exhaust.
22. In an internal combustion engine of the four-cycle type having admission and 30 exhaust ports extending through the wall of the cylinder, a slide valve controlling said ports, means for imparting a reciprocatory motion to the slide valve, and means for causing the movement of the slide valve 35 to be arrested for a period between the intake and the exhaust, comprising a link pivoted at one end to a fixed pivot and having its other end connected to the means for imparting the reciprocatory motion to the 40 slide valve.

In testimony whereof I affix my signature.
